FOLDABLE PORTFOLIO WITH AN ADJUSTABLE EASEL

Murphy Dennis Cudahy III, 2037 Beverly Place, South
Bend, Ind. 46616, and Joseph Lloyd Mossey, 59483
Clover Road, Mishawaka, Ind. 46544

Filed June 3, 1974, Ser. No. 475,401

Term of patent 7 years

Int. Cl. D19—06

U.S. Cl. D19—35

FIG. 1 is a perspective view of a foldable portfolio with an adjustable easel showing our new design in a fully opened condition;

FIG. 2 is a front elevational view thereof;

FIG. 3 is a left side elevational view; and

FIG. 4 is a left side elevational view thereof shown in a closed condition.

We claim:

The ornamental design for a foldable portfolio with an adjustable easel, as shown and described.
